UNITED STATES PATENT OFFICE

2,578,572

SPRAY GUN KEEPER

Francis F. Melvin and Joe O. Stevens, Elwood,
Ind.; said Stevens assignor to said Melvin

Application May 23, 1945, Serial No. 595,450

2 Claims. (Cl. 134—201)

1

This invention relates to means for storing or holding spray guns such as are used in applying paints and coatings, and has for a primary object the holding of the gun in such a manner that the inner air channels of the spray gun including the valve seats are kept free of a thinner fluid while the critical fluid tip is maintained in a submerged position in the fluid.

The fluid tip of the spray gun is an extremely critical item, and its orifices must be kept free from paint pigment which would tend to otherwise solidify therein after the gun had been in use and then laid aside for a period of time. Needles also are critical and must be kept free of the pigment so that when the gun is again put into operation, all passageways will be free of dried or semi-dried pigment and the gun can function properly. It has been the common practice to drop the assembled spray gun into a bucket of thinner in order to dissolve or prevent solidification of the paint pigment, but such practice carries the pigment into the inner air channels of the spray gun, tending to deposit some upon the valve seat causing leaks of air or spraying fluid with the resultant improper functioning of the gun. It has also been the practice to remove the tips and drop them into a can of thinner to allow the tip to drop to the bottom of the can, and in such practice the paint pigment taken up by the thinner will eventually settle to the bottom and in or on the tip.

To overcome these difficulties and provide a device insuring the proper cleaning of the critical parts of the spray gun which normally are contacted by the sprayed fluid, we have devised a spray gun tank which is illustrated in the accompanying drawings, in which

Fig. 1 is a top plan view of the tank with the cover broken away;

Fig. 2, a view in side elevation with the major portion of the side wall broken away;

Fig. 3, a view in transverse, vertical section on the line 3—3 in Fig. 1;

Fig. 4, a view in transverse vertical section on the line 4—4 in Fig. 1; and

Fig. 5, a view in top perspective of a wire rack carried within the tank.

Like characters of reference indicate like parts throughout the several views in the drawings.

In the present form of the invention the tank 10 is formed to have a rectangular shape and is preferably provided with a hinged top cover 11 so as to not only retard the evaporation of the thinner or cleaning fluid carried in the tank but also to prevent foreign matter from dropping therein. Within this tank 10 is carried a wire rack generally designated by the numeral 12. This rack 12 is made to have a pair of upper, spaced apart wires 13 and 14 secured by their ends to the cross bars 15 and 16. From the outer

2

ends of the cross bar 15, down-turned legs 17 and 18 extend to terminate preferably by inturned ends 19 and 20 respectively to form feet to rest on the floor 21 of the tank 10. In the same manner the cross bar 16 carries at its ends the down-turned legs 22 and 23 which in turn have the in-turned ends 24 and 25 serving as feet to rest on the floor 21. The wires 16, 22, and 23 form in effect an inverted U frame, and the wires 15, 17, and 18 form a second U frame.

The longitudinally disposed wires 13 and 14 have downwardly looped bends 26 and 27 respectively therein. The legs 17 and 18 are tied together by a cross bar 28 spaced intermediate the bar 15 and the lower ends 19 and 20. The legs 22 and 23 are tied together by a plurality of bars 29 herein shown as four in number, the lowermost of these bars being substantially at a mid-point of the legs 22 and 23.

20 A bar 30 has one end secured to the leg 17, herein shown as below the bar 28, and extends horizontally inside of and in contact with the leg 22 to be secured thereto, and then extends on in the same line to bend into a transverse bar 31 which in turn bends around into the bar 32. This bar 32 extends inside of the leg 23 to be secured thereto and continues on to the leg 18 to be attached thereto by its end. A plurality of bars 33 are carried by the end portions of the bars 30 and 32 which project beyond the legs 22 and 23, these bars 33 being herein shown as four in number.

25 A wire 34 is attached to the cross bar 15 between the leg 18 and the bar 14 and extends horizontally a distance therefrom, and then is bent vertically downwardly to merge into L-shape form into a major length 35 which extends horizontally above the ends 19 and 20 and terminates by an end portion 36 which is bent around to be secured by its end to the leg 17 below the bar 30.

30 Preferably the wire 13 is carried at a slightly higher elevation than is the wire 14 and to accomplish this, the wire 14 is secured to the undersides of the bars 15 and 16, and the bar 13 is secured across the topsides thereof.

35 The frame 12 thus described is placed within the tank 10, the frame being so proportioned that the respective legs 17, 18, 22, and 23 will be in substantial contact with the inner faces of the two side walls of the tank so as to prevent side shifting of the frame therein. Then with the frame positioned in the tank 10 to have the cross bar 31 in contact with an end of the tank, there is sufficient room left between the bar 15 and the open end of the tank to permit insertion therebetween of a can 37 to rest on the wire portion 35 with the bottom of the can in abutment with the vertical portion of the wire 34.

40 The can 37 is provided with a plunger 38 normally urged outwardly by the spring 39 to close

an opening in the can in the usual manner of a spring seated valve, the details of which do not enter into our invention. However, an end of the plunger 38 compressibly abuts the inner face of the side wall of the tank to hold the plunger 38 in a retracted position in opposition to the spring 39, the wire 34 preventing inwardly shifting of the can 37 bodily.

The can 37 is so designed in respect to the position of the plunger 38 that when the tank 10 has the cleaner or thinner fluid 40 placed therein to a level substantially as indicated in Fig. 2, which is above the bars 33, the fluid within the can 37 (the can serving as a reservoir) will feed out from the can 37 to maintain that approximate level of the fluid throughout the tank. Some loss of the fluid will be had by evaporation, and other loss will be had by reason of some of the fluid adhering to the spray guns and tips when they are removed from the fluid. Therefore, the automatic level maintaining means is provided, not only to maintain an adequate supply of the cleaning fluid 40 within the tank 10, but also to prevent the level from reaching a predetermined height.

In use, the spray gun 41 is laid across the wires 13 and 14 to rest in aligned bends 26 and 27 to have the spray tip end of the gun hanging downwardly with the air inlet end substantially horizontally disposed as indicated primarily in Fig. 3. The level of the fluid 40 has been predetermined to be just above the paint or coating inlet 42 of the gun so that the fluid may enter therein and also have the tip 43 submerged, while at the same time all of the valve parts are well above the cleaning fluid and not subject to entrance of that fluid therein. The bars 33 in conjunction with the vertically aligned bars 29 form a basket between the end and side walls of the tank 10 to receive thereon the surplus or extra spray tips 43 and hold them well above the floor 21 of the tank out of the path of any pigment tending to gravitate theretoward.

Thus, it is to be seen that we have provided a very simple and yet a most effective device for holding spray guns and tips when not in use in such a manner as to keep them clean and not exposed to flow of fluid into certain parts of the gun where damage would be caused thereby.

While we have described our invention in the one particular form in more or less minute detail, it is obvious that structural variations may be employed without departing from the spirit of the invention, and we, therefore, do not desire to be limited to that precise form beyond the limitations as may be imposed by the following claims.

We claim:

1. For supporting spray gun nozzle ends in a bath of fluid contained in a tank, a wire rack comprising a pair of inverted substantially U-shaped frames; a horizontally disposed wire interconnecting respectively the legs on each side

of said frames in parallel relation; said wires being spaced below the tops of said frames and extending horizontally beyond one of said frames; transverse wires secured across said extending wire ends outside of one said frame; a pair of horizontally disposed support wires, spaced apart in parallel relation interconnecting the tops of said frames, said last wires having bends therealong to serve as longitudinal spacers; said horizontally disposed transverse wires being between a wall of said fluid tank and said one frame to form a skeleton basket floor; additional wires secured across the legs of said end frame vertically spaced above said first transverse wires; and an L-shaped wire secured to and positioned in spaced relation outside of said other end frame, to have one leg vertically disposed and interconnected with the top of said other frame, and a horizontally disposed leg interconnected therebelow to a leg of said other frame; and a fluid reservoir tank having a horizontal width to fit snugly between said other frame and its adjacent fluid tank wall to rest on said horizontal leg of said L-shaped wire, to maintain said basket floor in contact with the opposite wall of said fluid tank.

2. For supporting a spray gun nozzle end in a bath of fluid contained in a tank, a wire rack formed to fit within the tank and comprising a pair of longitudinally extending, transversely spaced apart gun carrying wires; a pair of wire members engaging end portions of said carrying wires and extending therefrom by portions to be carried by said tank; a basket carried by one of said wire members, spaced below said carrying wires and extending longitudinally outwardly beyond said one wire member; a fluid reservoir tank; and a reservoir tank carrying member extending longitudinally outwardly beyond said other wire member, and spaced below said gun carrying wires; said rack being proportioned to receive said reservoir tank as a spacer member between said other wire member and one of the walls of said fluid tank to have said basket in contact with the opposite end wall of the fluid tank, whereby the reservoir tank is supported by said reservoir tank carrying member and is substantially in contact with said one tank wall and said other wire member.

FRANCIS F. MELVIN.
